UNITED STATES PATENT OFFICE.

MARK A. SMITH AND CHARLES F. YAEGER, OF EVANSVILLE, INDIANA;
SAID SMITH ASSIGNOR TO SAID YAEGER.

BROOM-WIRING MACHINE.

SPECIFICATION forming part of Letters Patent No. 355,224, dated December 28, 1886.

Application filed January 30, 1886. Serial No. 190,319. (Model.)

To all whom it may concern:

Be it known that we, MARK A. SMITH and CHARLES F. YAEGER, citizens of the United States, residing at Evansville, in the county of 5 Vanderburg and State of Indiana, have invented certain new and useful Improvements in Broom-Wiring Machines and Presses; and we do declare the following to be a full, clear, and exact description of the invention, such as will 10 enable others skilled in the art to which it app pertains to make and use the same, reference being had to the accompanying drawings, and to letters or figures of reference marked thereon, which form a part of this specification.

15 Figure 1 of the drawings is a representation of a front elevation. Fig. 2 is a vertical central sectional view. Fig. 3 is a vertical section showing the movable jaw. Fig. 4 is a section showing the stationary jaw. Figs. 5, 6, 20 and 7 are detail views.

Our invention relates to machines for flattening and holding brooms while the metallic binding-wires and the bridle are being secured thereon; and it consists in the construction and 25 novel combination of parts, as hereinafter set forth, and pointed out in the claims.

Referring by letter to the accompanying drawings, A designates the bed-plate, which is provided in its upper face with the two longitudinal parallel ribs B B', which extend 30 through recesses in the lower ends of the stationary upright C and the hinged upright D.

The lower end of the stationary upright C is secured to the bed-plate by mortises, tenons, 35 and locking-pins, after the usual manner of framing timbers.

The hinged upright D is pivoted to the horizontal ribs B B' by a transverse bolt-rod, C', passed through the lower recessed end of the 40 hinged upright and through the horizontal parallel longitudinal ribs B B'. The stationary upright C is provided on its inner face with a fixed clamping-jaw, E, which projects above the upper end of the body portion of said upright, and this jaw E is provided with a horizontal transverse groove, F, in its inner face, to receive one-half, or thereabout, of each of the two binding-wires or bridle-wires G^x G^x, which are used in our improved construction 45 of brooms.

H designates a spring, secured at its lower

end to the stationary upright, and bearing at its upper end against the hinged upright, the object of which is to hold the hinged upright normally open or away from the stationary 55 upright.

The hinged upright D is also provided with a clamping-jaw, I, which has in its inner face a horizontal transverse groove, I', which is opposed to the transverse groove F, and is designed to receive the other half, or thereabout, 60 of each of the two binding-wires used in our improved construction of binding brooms.

The hinged upright D is provided near its lower end with slotted guide-flanges G G' on 65 its inner face near its edges, in the slots K of which the hinge-rod K' for the lower arms, N N', of the compressor-plates M M works. The upper arms, L L', of the compressor-plates are hinged to the upper ends of the lower arms, 70 N N', and these compressor-plates are in the shape of flanged formers, to give outline to the upper portion of the broom-body. Metal straps O O' are pivoted to the edges of the stationary upright near its upper end, and extend horizontally across and beyond the hinged upright, and between the projecting ends of said metal straps is pivoted a compression-lever or cam-lever, P, the function of which is to compress 75 and hold the hinged upright and its compressor-plate against the broom-body when the latter is in place ready to be wire-bound and bridled.

The clamping-jaw E is provided with a cross-rod at its upper end, at the middle of 85 which is fulcrumed a bending-lever, Q. The lever Q is provided with a grooved toe or point, Q^x, the groove being made vertical therein to fit the wire S—that is, to be bent over the bridle-wires. This wire S is to be 90 first provided with a bend, S', at each end, and then cut to the proper length to form two cross-wires, S. The bending-lever Q is connected by a link-rod, Q', to a second lever, Q², fulcrumed on a bracket, Q³, secured in or to 95 the outer face of the stationary upright.

The broom-blank is first put in place in the broom-former and the cam-lever operated to clamp it in place. The cross-wire S is then introduced through a slot, S², in the upper 100 portion of the compressor-plate of the hinged jaw or upright and passed through the broom-

body for the purpose of bringing the unbent end of said cross-wire in contact with the grooved heel of the bending-lever Q. By a downward movement of the lever Q the cross-wire S is locked in place by bending the unbent end of the cross-wire S up over the bridle-wires, the grooved end of the bending-lever engaging the cross-wire and forming the hook on the unbent end of the latter. A pivoted lever, V, is connected by a rod or arm, V', to one of the compressor-arms, and the outer end of this lever V is provided with handle W, the power end or handle of said angle-lever passing through a vertical slot, W', provided with a detent-rack, W², to hold the lever to its adjustments, said vertical slot W' being made through the stationary upright near one edge of the same. By this construction the compressor-plates can be raised or lowered to elevate or depress the broom-blank to enable the operator to properly wire the broom while in the machine. The encircling wire that is commonly used around the butts of the broom-straw is also used with these binding-wires, and is placed on in any well-known manner prior to the time of applying our improved binding-wires.

Having described this invention, what we claim, and desire to secure by Letters Patent, is—

1. The combination, with the bed-plate having the stationary upright provided with the transversely-grooved clamping-jaw with the vertical middle slot, the bending-lever with the vertically-grooved toe, the power-lever, and the hook-rod connecting the bending and power levers, of the hinged upright with the transversely-grooved clamping-jaw with middle slot, the hinged compressor-plates, and 40 the cam-lever fulcrumed between the pivoted

horizontal strap-arms secured to the stationary uprights, substantially as specified.

2. The combination, with the stationary upright and the hinged upright secured to the base, and provided at their upper ends with 45 the rigid transversely-grooved clamping-jaws having vertical middle slots in their transverse grooves, of the pivoted strap-arms with cam-lever, the hinged adjustable compressor-plates, the bending - lever with vertically- 50 grooved toe, the power-lever, and the hook-rod connecting the power-lever and bending-lever, substantially as specified.

3. The combination, with the bed-plate having the stationary upright and the hinged upright, the transversely-grooved clamping-jaws with vertical middle slots, the bending-lever connecting with the power-lever, and the compressor-plates having the hinged arms connected by a cross-rod working in slots in 60 flanged arms on the hinged upright, of the pivoted angle - lever having its power end working in a rack-slot in the stationary upright, and connected by a vertical pivot-arm to one of the compressor-plates, substantially 65 as specified.

4. The combination, with the bed-plate, stationary upright, hinged upright, and transversely-grooved clamping-jaws, with middle vertical slots intersecting their grooves, of the 70 clamping-lever, the compressor-plates, and the vertically - grooved bending - lever connected with a power-lever, substantially as specified.

In testimony whereof we affix our signatures in presence of two witnesses.

MARK A. SMITH.
CHARLES F. YAEGER.
